HYDRAULIC PUMPING JACK

Herbert M. Salentine, Los Angeles, Calif.

Application December 27, 1935, Serial No. 56,308

5 Claims. (CL. 121—164)

My invention relates to hydraulic pumping jacks and to methods of pumping wells. This application is a continuation in part of my co-pending application for Oil well pumping systems, Serial No. 605,916, filed April 18, 1932, now Patent 2,073,809, as to common subject matter.

The characteristic production cycle of an oil well begins with a flush period in which the oil flows by reason of subterranean pressure, gradually subsiding until it is necessary that the well be placed "on the pump". As the life of the well progresses, the quantity of oil obtained decreases and its quality deteriorates. Usually more and more water is brought in with the oil; also, as the pressure on the oil decreases, the lighter fractions change to gas and escape so that the remaining oil increases in viscosity with the result that its flow into the well bore is slower. By reason of the increased viscosity and surface tension of the oil, the tendency for sand to enter the well bore is increased.

In each well there are a number of variables which in their various combinations provide an infinite variety of conditions. For example, the fluid level and also the rate of flow into the well bore, which in itself has several contributing variables, changes the viscosity of the oil and the formation pressure whether due to gas or water urge.

These several variables are increasingly important as the well reaches its final stage of production. Naturally, as the cost of production per barrel oil increases, the yield is low; therefore, the ability of the pumping apparatus to meet the particular conditions existing becomes increasingly important. These various factors cannot readily be determined before the pumping apparatus is installed but require, first, installation of the apparatus, and then adjustment to meet the conditions.

Within the pumping apparatus itself, it is necessary to maintain a pressure difference tending to urge the oil into the pumping apparatus, but this pressure difference should be as low, and preferably as nearly constant as possible. The reason for this is that as the pressure diminishes, dissolved gases in the oil are freed, and back pressure differences materially exceeding the average, although existing for short intervals, have a tendency to liberate the dissolved gases which do not readily redissolve when the pressure difference drops; thereby decreasing the volumetric efficiency of the pumping apparatus, and further increasing the viscosity of the oil.

In consideration of the problem as outlined above, among the objects of my invention are:

First, to provide a hydraulic pumping jack which is adapted to operate well pumps of comparatively shallow wells, such as those requiring a lift from a few hundred to two or three thousand feet.

Second, to provide a hydraulic pumping jack which is particularly designed for "stripper" wells; that is, wells which are in the last stages of production.

Third, to provide a pumping jack of this character in which special provision is made for a wide range of adjustment to meet the manifold variations of pumping conditions determined by the rate of flow of oil into the well; the viscosity and specific gravity of the oil; the amount of deleterious matter present, such as water or sand; the crookedness of the well bore; and the pumping depth.

Fourth, to provide a pumping jack which incorporates a cushion means operable at the end of the down stroke, and means whereby the cushioning effect may be varied to meet well conditions.

Fifth, to provide a hydraulic pumping jack which incorporates means whereby the initial interval of the up stroke may be rapid, as compared to the remainder of the up stroke, so that a minimum of time is lost in restretching the sucker rod string prior to beginning the up stroke of the pump plunger attached to its lower end, and a maximum of the total cycle may be devoted to the pumping stroke.

Sixth, to provide a pumping jack which may be installed on wells in which the derrick and other surface equipment has been removed.

Seventh, to provide a hydraulic pumping jack which may be operated with or without provision for counterbalancing of the sucker rods, depending upon the depth of the well.

Eighth, to provide a hydraulic pumping jack wherein counterbalancing means for the sucker rods may be incorporated with only superficial changes in the jack; such changes being in the nature of additions whereby a single jack design may be used for both uncounterbalanced and counterbalanced installations.

Ninth, to provide a hydraulic pumping jack wherein the jack cylinder may be supported directly upon the well casing in centered relation thereto, thereby eliminating need for other support.

Tenth, to provide a hydraulic jack which is particularly compact and which provides a uni-

tary jack cylinder base and a control valve housing so arranged as to minimize extraneous pipe.

Eleventh, to provide a hydraulic pumping jack which incorporates a novel sealing means through 5 which the polish rod extends, and from which any leakage is drained into the return or low pressure side of the operating fluid circuit.

Twelfth, to provide a hydraulic jack which is particularly durable, efficient in its action, and 10 capable of withstanding long and continued use without deterioration.

With the above and other objects in view as may appear hereinafter, attention is directed to the drawings, in which:

15 Fig. 1 is a fragmentary elevational view of my hydraulic pumping jack, showing substantially diagrammatically the operating fluid circuit including the pump and storage tank.

Fig. 2 is an enlarged, fragmentary, sectional view of the hydraulic jack taken through 2—2 of Fig. 1, with parts and portions shown in elevation, illustrating the base of the jack cylinder, and showing particularly the cushioning means and the arrangement whereby the cushioning 25 effect may be varied.

Fig. 3 is a similar, fragmentary, sectional view through 3—3 of Fig. 2, showing particularly the control valve in the position for delivering operating fluid into the jack cylinder.

30 Fig. 4 is a fragmentary sectional view of the control valve similar to Fig. 3 but showing the valve in the position for permitting discharge of fluid from the jack cylinder as well as by-passing fluid from the pump back to the storage tank, and 35 indicating further by dotted lines the manner in which discharge from the jack cylinder may be throttled.

Fig. 5 is a fragmentary sectional view similar to Fig. 3 but illustrating a modified form of 40 cushioning means which also incorporates an arrangement whereby rapid movement may be obtained during the initial part of the up stroke.

Fig. 6 is an enlarged, fragmentary, sectional view showing the upper portion of the jack cylinder, the trip rod retaining means, and the manner in which the polish rod projects above the 45 jack cylinder.

Fig. 7 is a partially elevational, partially transverse sectional view through 7—7 of Fig. 6.

50 Fig. 8 is a fragmentary, partially diagrammatical view of the pressure pump in which a pressure tank and a pressure maintaining means is substituted for the storage tank, and the operating fluid circuit is maintained under a pressure to 55 counterbalance partially the weight of the sucker rods.

Fig. 9 is a composite graph illustrating representative stroke characteristics obtainable with the hydraulic jack, and showing for comparison 60 the stroke characteristic of the conventional walking beam and pitman drive.

My hydraulic pumping jack comprises generally a jack piston and cylinder means 1, a combined cylinder base and valve housing 2, a valve 65 operating mechanism 3, a pump 4, and a storage chamber 5. The jack cylinder base 2 has a modified form indicated by 6 in Fig. 5, and the storage chamber 5 may be substituted by a pressure tank 7 and pressure maintaining means 8, as shown in 70 Fig. 8.

The combined jack cylinder base and control valve housing 2 is in the form of a casting having an externally threaded lower end adapted to screw into a coupling A, or other fitting, forming 75 the upper end of the oil well tubing, not shown.

The base 2 is provided with a bore 12 therethrough which receives a polish rod 13. The lower end of said bore is provided with a packing gland 14. Above the packing gland 14, the bore 12 is provided with an enlargement 15 which is 5 adapted to be connected with the low pressure side of the operating fluid circuit, as will be brought out hereinafter. Above the enlargement 15, the polish rod 13 fits snugly, though slidably, within the bore so that the amount of fluid entering the enlargement 15 is minimized. With this arrangement, the packing gland 14 is not subjected to the pressures existing in the jack piston and cylinder means.

The upper end of the base member 2 is provided with a socket 16 which is annular at its 15 lower portion so that the upper part of the bore 12 is within a hollow boss 17. The upper end of the base 2 receives the lower end of the jack cylinder 18 forming part of the piston and cylinder means 1. The jack cylinder 18 is a length 20 of pipe or tubing, the upper end of which is screw-threaded into a cylinder head 19, shown best in Fig. 6.

The cylinder 18 receives a piston 20 mounted 25 on a piston sleeve 21. The piston sleeve 21 receives the polish rod 13, and both of these members project through the cylinder head 19. Air relief ports 22 may be provided in the cylinder head, as shown in Fig. 6. The upper end of the piston sleeve, however, carries a packing gland 23 which fits around the projecting end of the 30 polish rod to seal the annular space between the sleeve and polish rod.

The projecting end of the polish rod is adapted 35 to receive a clamp 24 to prevent downward movement thereof relative to the sleeve 21. With this arrangement, the position of the polish rod may be adjusted after the pumping jack has been installed without dismantling or otherwise disturbing 40 the pumping jack.

At one side of the base member 2 there is provided an enlargement which forms a valve housing, as shown best in Figs. 1, 3, and 4; said housing is provided with a cylindrical valve chamber 45 25 which extends horizontally or at right-angles to the bore 12 and is provided with a jack cylinder port 26 which extends laterally and intersects the lower end of the socket 16. Below and parallel with the valve chamber, is an intake passage 27 which has upwardly extending ports 28 intersecting the valve chamber at either side and below its horizontal axis. Similarly, above the valve chamber 25 and in parallel relationship therewith, is a discharge passage 29 having ports 30 50 extending downwardly and intersecting the valve chamber at either side and above its horizontal axis.

The valve chamber 25 receives an oscillatable valve 31 having at its side adjacent the jack 60 chamber port 26 a recess 32 which, depending upon the position of the valve member, connects the jack chamber port with either or both the intake passage 27 and exhaust passage 29 by means of their corresponding ports 28 and 30. 65 On the opposite or outer side, the valve member 31 is provided with an arcuate channel 33 which forms between its points of intersection with the periphery of the valve member a sealing bar 34. When the recess 32 connects the jack cylinder 70 port 26 with the intake passage 27, the sealing bar seals communication between this passage and the exhaust passage 29, as shown in Fig. 3. When the jack cylinder port 26 is connected with the discharge passage 29, the passage 33 also connects 75

the intake passage 27 with said discharge passage 29. The valve member is so arranged that the communication between jack cylinder port 26 and the discharge passage 29 may be throttled, and in certain positions some of the fluid from the intake port may be diverted therethrough so that the rate of discharge of fluid from the jack cylinder may be varied by adjusting the corresponding extreme position of the valve member.

10 The valve member 31 is provided with a stem which extends through one end of the valve housing and receives the lever 35 which extends toward the main part of the base 2, as shown in Fig. 1. The lever is connected to a yoke 36 in which is threaded the lower end of a trip rod 37, there being provided a locknut for adjustably securing the trip rod in the yoke member 36. The trip rod 37 adjustably receives a spring cup 38 which may be threaded thereon and also secured by a locknut. The spring cup 38 receives an adjustable spacer sleeve 39 and a spring 40, as shown best in Fig. 2.

15 A second spring cup 41 is slidably mounted upon the trip rod 37 and is likewise provided with an adjustable stop sleeve 42 and spring 43. The spring cup 41 is provided with a laterally extending lug 44 which adjustably receives the lower end of a connecting rod 45. The trip rod 37 and connecting rod 45 extend upwardly in contiguous relation to the jack cylinder and head 19. The upper end of the head 19 is reduced in section to receive a collar 46 having a guide bracket 47 extending laterally therefrom, and through which project the trip rod 37 and connecting rod 45.

20 35 The upper end of the piston sleeve 21 below its packing gland 23 supports a collar 48 having a laterally extending arm 49, the extremity of which receives the upper end of the connecting rod 45 so that the connecting rod is raised and lowered with movement of the piston 20 and its sleeve.

40 45 The upper end of the trip rod 37 which projects through the guide bracket 47 is provided with a cam collar 50 having flat faces which converge downwardly, and other faces converging upwardly which are engaged by similarly shaped cam riders 51 supported by leaf springs 52 which extend upwardly from the bracket 47, as shown best in Figs. 1 and 6.

50 55 The lower end of the piston sleeve 21 is provided with an inverted cup 53 which is adapted to fit over and coat with the boss 17 to form a dashpot for cushioning the down stroke of the piston at its extremity. The extent of the cushioning or dashpot action is dependent upon adjustment of the spring cup 38, for the piston moves downwardly until the spring cup 41 engages the spring 40 and its cup 38 with sufficient force to reverse the valve; that is, move the valve from the position shown in Fig. 4 to that shown in Fig. 3. The effect of this dashpot action is discussed more in detail hereinafter.

55 60 Mounted on the side of the base 2, above and below the lever 35, are set screws 54 and 55. Set screw 54 limits downward movement of the lever and consequently the port opening between the jack cylinder port 26 and the intake passage 27, and thereby determines the position of the valve shown in Fig. 3. The set screw 55 similarly controls the port between the jack cylinder port 26 and the exhaust passage 29, as shown in Fig. 4. Usually the communication between the intake passage 27 and the jack cylinder port 26, as determined by set screw 54, is wide open so that the

capacity of the pump 4 at the particular speed with which it runs determines the speed of the piston during its up stroke. However, regulation by set screw 54 is particularly useful in adjusting the hydraulic pumping jack to a given well. After the desired time interval for the up stroke is determined, permanent adjustment is preferably made by regulating the speed of the pump or by substituting a pump 4 of the required capacity.

10 15 As shown in Fig. 1, the intake passage 27 is connected by a pipe 56 to the discharge end of the pump 4; while the discharge passage 29 is connected by a pipe 57, preferably larger than pipe 56, with the storage tank 5 and a suitable pipe 58 which may include in part the pipe 57 and which provides communication between the storage tank 5 and the intake of the pump 4.

20 25 A small pipe 59 may extend between the enlargement 15 and the outlet or exhaust passage 29, or at any suitable point of the return circuit of the operating fluid. Similarly, a tube 60 communicates between the head 19 and the return circuit. Thus, any fluid escaping through the bore 12 or through the enlargement or pocket 15, or working past the piston 20 is returned to the storage tank.

30 35 Attention is now directed to Fig. 5 in which is illustrated a modified cylinder base and control valve housing 6. This structure is in most respects similar to the base 2; like characters 30 designating the similar parts. In place of the recess 16, the jack cylinder base 6 is provided with a recess 61 at its upper end equal in diameter to the inside of the jack cylinder 18 and extending a short distance below. Beneath recess 61, is provided a smaller recess or socket 62, below which is the bore 12. The jack cylinder port 26 of the control valve intersects the bottom of the socket 62.

40 45 In place of the inverted cup member 53, the lower end of the piston sleeve 21 is provided with a ram sleeve 63 through which extends the polish rod 13. The ram 63 forms a snug sliding fit within the socket 62 when the piston approaches the lower end of its stroke.

50 55 A by-pass 64 extends from the recess 61 to the socket 62; said by-pass is provided with a check valve 65 for preventing flow from the socket 62 to the recess 61, and a needle valve or other suitable throttling valve 66 which determines the rate of discharge from the recess 61 and jack cylinder into the socket 62.

60 65 In addition to the by-pass 64, a second and preferably larger by-pass 67 is provided between the recess 61 and the exhaust or outlet passage 55 29 of the control valve. Said by-pass 67 is provided with a check valve 68 which permits flow from the outlet passage 29 into the jack cylinder whenever the pressure in the cylinder is less than that in the discharge passage.

70 75 With the arrangement shown in Fig. 5, the downward movement of the piston 21 is cushioned and retarded when the ram 63 enters the socket 62, inasmuch as the fluid from under the piston may now flow only through the by-pass 64. However, the ram 63 may be so arranged that a certain amount of leakage may occur during its initial movement into the socket 62; which leakage gradually decreases as the ram enters its socket, thereby providing a gradual 70 checking in the downward movement of the piston. At the beginning of the up stroke, the operating fluid coming through port 26 acts only upon the ram 63. Because the diameter of this ram is smaller than the piston, a given 75

amount of fluid causes a more rapid movement thereof. During this initial movement, the check valve 68 prevents the formation of a negative pressure below the piston 20 and maintains the recess 61 completely full of liquid; thus when the ram clears the socket 62, the force of the operating fluid is applied against the entire under-surface of the piston; and inasmuch as the area of the recess 61 and jack cylinder 18 is larger than the socket 62, the remaining upward movement of the piston is at a lower rate than its initial movement. The effect of this is shown in Fig. 9 and is discussed in more detail hereinafter.

The structures so far described do not provide for any counterbalancing of the sucker rods, and such counterbalancing is unnecessary in the shallower wells. As the depth of the fluid level increases, counterbalancing becomes more and more necessary in order to maintain efficient operation. The practical depth of a well pump operated by the apparatus may be increased by maintaining a pressure in the storage tank 5. This can be readily accomplished inasmuch as the fluid circulating system is a closed one. In the event that back pressure is maintained, the force of such back pressure on the piston 18 is of course less than the weight of the rods, so that such excess weight of the rods may be utilized to cause return movement of the piston. Such counterbalancing may be accomplished by means of the pressure tank 7 which is substituted for the storage chamber 5. Said pressure tank 7 comprises a base 11 and a cylinder 72 in which is mounted a floating diaphragm or piston 73 which divides the cylinder 72 into an upper or air chamber 74 and a lower or operating liquid chamber 75. The pressure maintaining means 8 is formed within a housing 80 which may constitute the head of the cylinder 72. Within said housing 80, there is formed a major cylinder 81 and a coaxial minor cylinder 82 which receive a dual piston 83 comprising a major piston element 84 and a minor piston element 85. Said piston elements fit into the cylinders 81 and 82 respectively.

The chamber formed in the major cylinder between the major piston element 84 and the minor cylinder is connected with the air chamber of the pressure tank 7 through a port 86, and in addition, is provided with a spring 87 tending to urge the dual piston in a direction which withdraws the minor piston element from its cylinder. The chamber formed in the opposite side of the major piston element is connected by a pipe 89 to a suitable point in the pressure side of the operating fluid circuit; the pressure, in which, drops when the pump 4 delivers back into the return line.

The cylinder 82 is connected by a port 90 through an intake check valve 91 to the atmosphere, and through an outlet check valve 92 to the interior of the counterbalancing chamber 8.

With each cycle of operation of the hydraulic jack, the dual piston 83 reciprocates and pumps a quantity of air into the upper or air chamber 74 of the pressure tank. A relief valve 93 may be incorporated in the pressure maintaining means to relieve the pressure in the air chamber should it exceed a predetermined value.

The purpose of the diaphragm 73 is to separate the cushioning air within the chamber 74 from the liquid circulating system in order to prevent dissolving of the air into the liquid. The liquid within the circulating system is, therefore, sub-

stantially free of gas and, substantially therefore, incompressible; thereby eliminating any loss of time which might otherwise be consumed in compressing a compressible medium. It is possible with this arrangement to maintain the liquid in the circulating system under considerable pressure although the pressure difference on opposite sides of the pump may be kept with a reasonable value. This enables the hydraulic jack to operate a well pump at a deeper level than is feasible without counterbalancing.

As stated hereinbefore, each well has characteristics different from all others; consequently, in order that my hydraulic jack may be installed to meet most effectively the conditions existing at a particular well and also to facilitate experimenting with and testing of the well to determine just what will prove the most efficient pumping cycle and rate, a number of adjustable elements are provided. Thus, the set screws 54 and 55 regulate the extent of movement of the valve element 31; by so doing, it is possible to regulate independently the up stroke and the down stroke of the jack, as well as the rapidity of the pumping cycle as a whole.

Inasmuch as high pressure pumps, such as the pump 4 used to circulate the operating fluid, operate most efficiently within a particular speed range, it is preferable that, for continuous operation, the port to the jack cylinder be wide open during the intake stroke. First, however, it is necessary to determine what quantity of fluid per minute should be delivered to the jack cylinder. Therefore, during initial testing of the well and determining of the variable factors thereof, the set screw 54 is particularly useful. After the test is completed, the proper size pump 4 may be installed, if need be, for permanent operation, and the set screw backed down to provide full opening of the valve.

The set screw 55 likewise serves particularly during the testing period of the well, and is locked once the desired rate of discharge from the jack cylinder is determined. However, as the delivery from the well gradually subsides, quite likely with increase in viscosity of the oil, the set screw 55 may be adjusted to increase the duration of the down stroke and consequently the period of the entire cycle commensurate with the reduced quantity of oil available.

The duration of the down stroke, as well as the cushioning effect, may also be regulated by adjustment of the spring cup 38 which determines the position of the piston 20 and dashpot element 53, as shown in Fig. 2. With the arrangement shown in Fig. 5, either or both the cup 38 and valve 66 may be utilized for this purpose.

Inasmuch as the length of stroke of the jack is determined by the stroke for which the well pump is designed, plus the stretch in the sucker rods which is dependent upon the depth of the well, the collar 31a on the trip rod 31 provides a ready and convenient adjustment of the stroke length to meet this variable.

The springs 43 and 40 are first compressed until the valve starts to change its position and then expand to force the valve to complete its movement, thus insuring full movement of the valve. It should be here noted that the passage 33 through the valve member 31 is smaller at its end communicating with the outlet or return passage 29 than with the intake passage 27. Therefore, the valve member is urged upwardly by hydraulic pressure, particularly when in the position shown in Fig. 3; thus facilitating proper

sealing of the outlet passage 29 from the intake passage 27 during delivery of fluids to the jack cylinder. With this arrangement, leakage due to wear of the valve member is minimized.

5 Attention is now directed to Fig. 9. The upper chart, designated A, indicates a conventional pumping cycle of the "crankpin type" as obtained by a walking beam and pitman drive. Chart B illustrates the typical cycle obtained by my hydraulic pumping jack as arranged in Fig. 2; while chart C illustrates the typical cycle obtained with the arrangement shown in Fig. 5.

In each chart, the upper or solid line represents the movement of the polish rod, while the lower 15 or dotted line represents the movement of the well pump plunger which carries the traveling valve. The distance between the two lines indicates the rod string stretch, while the slope of the lines indicates the velocity.

20 Several factors should be borne in mind; first, the quantity of gas which is capable of going into solution with a liquid such as crude oil varies inversely as the pressure; second, the space occupied by the dissolved gas in a liquid varies inversely as the pressure; third, when the pressure on the liquid exceeds the critical pressure of the normally gaseous substance, such substance is in solution as a liquid. Thus, as the pressure on crude oil is lowered, gas is freed and the remaining liquid increases in viscosity.

The greater the pressure drop, whether between the formation and well bore or elsewhere, the greater is the amount of gas freed; also the rate of flow into the well bore is increased. This 35 tends to increase the amount of sand and other deleterious matter carried into the well bore by the oil and is due not only to increased velocity but also to the increased viscosity and surface tension of the oil under its lowered pressure.

40 The fluid level in a well bore at which the most efficient recovery may be had in view of the above factors is termed the "critical fluid level", and a certain amount of experimentation and testing of a particular well is necessary in order to determine this level.

45 There is a focal point at which the effect of gas being liberated due to decrease in fluid pressure becomes particularly noticeable, and this is in the intake chamber of the well pump between the standing and traveling valves. The greater the velocity of the traveling valve during the intake stroke of the pump, the greater the pressure drop between the fluid in the well bore and that within the intake chamber. Increase in the 50 pressure drop means a lower pressure within the intake chamber, resulting in an increased liberation of gas. This both reduces the volumetric efficiency of the pump and increases the viscosity of the liquid. Even though the minimum pressure 55 sure reached in the intake chamber is of short duration, gas is liberated which requires both time and agitation to redissolve. Inasmuch as the pressure on the liquid continues to diminish as the liquid reaches the surface through the 60 production string, very little, if any, of the released gas redissolves.

65 With the crankpin cycle, as shown in chart A, it will be noted that while the polish rod moves in a 50-50 cycle, the well pump plunger, due to the 70 taking up of the sucker rod stretch during the down stroke and re-stretching of the rods during the initial up stroke, must accomplish its up stroke in less than 50% of the cycle. This means that the plunger velocity during the up 75 or intake stroke is faster than the polish rod.

In addition, the peak velocity of the plunger, represented by the tangent line X, is greater than the average or straight line velocity represented by the line Y.

On the other hand, even the average velocity 5 represented by line Y is too fast for a given pumping cycle. With the cycle obtainable by my hydraulic jack, not only may the intake velocity of the well pump be substantially constant, but it may be materially slower than that 10 possible with the crank-pin cycle at the same pumping rate. As shown in charts B and C, the up stroke of the well pump plunger may occupy 15 70 to 80 percent, or more, of the total cycle. With the hydraulic jack, the downstroke 20 of the polish rod need occupy only a sufficient proportion of the total cycle to insure dropping of the well pump plunger and the sucker rod string by the action of gravity as modified by the character of the oil being pumped, the 25 straightness or crookedness of the hole, and other frictional factors. The polish rod, because of frictional resistance to movement of the well pump plunger, is free to drop faster than the plunger. For this reason, it is desirable to 30 cushion materially the otherwise sudden reversal of the polish rod, as indicated by the chart B, and still obtain the greatest possible up stroke duration. In other words, a substantially fixed time is required for the plunger to drop 35 back to its lower position, and this time may be utilized in any manner to provide for the most desirable movement of the polish rod in order to minimize excessive loads on the various parts of the pumping apparatus.

35 Due to the fact that the sucker rods are relatively long and are stretched by their own weight, the weight of the plunger, and, during the up stroke, the weight of fluid above the plunger, they are in effect an elongated spring. This 40 causes a certain amount of lost time in the pumping cycle whether by the crankpin cycle, as shown in chart A, or by the special cycle shown in chart B. This lost time may be materially reduced by rapidly raising the polish rod 45 during its initial up stroke as shown in chart C. The duration of the rapid portion of the up stroke is adjusted so that the normally slower portion of the up stroke begins before the well 50 pump plunger starts on its up stroke.

55 While at first it may appear that the rapid down stroke and comparatively rapid reversal of movement might set up undue stresses in the sucker rods, such is not the case. The greatest load occurs during the up stroke when the weight 60 of the fluid is added to the weight of the sucker rods and plunger. With the crank pin cycle, the velocity either maximum or average during the up stroke is materially greater than with my special cycle, so that the stresses on the rods are 65 necessarily greater with the crankpin cycle.

A further advantage is obtained with my special cycle which is particularly noticeable when the pumping rate may be only a few strokes per minute, as is the case with stripper wells. Because of the relatively long, slow, and uniform up stroke and the quick down stroke, it is impossible to set up surging in the well bore. With the crankpin cycle at slow speeds, a periodic impulse is applied to the fluid within the well bore. 70 If this impulse approximates the natural frequency of fluid oscillation, the fluid may be caused to surge up and down from its critical fluid level. This results in increased pressure difference between the well bore and the forma- 75

tion, increases the liberation of gas, renders the remaining fluid more viscous, and increases sanding troubles.

In order that the benefit of my special pumping cycle be obtained, the down stroke time of the polish rod should not exceed one-half its up stroke time.

My method of pumping wells is best exemplified by the special cycle charts B and C. Briefly, it consists in rapidly dropping the polish rod; then cushioning its downward movement as it reaches the lower end of its stroke, the duration of the entire downward stroke of the polish rod being approximately equal to or less than the interval required for the plunger of the well pump piston to reach its bottom position under the influence of gravity as modified by frictional resistance; then slowly raising the polish rod at a substantially uniform rate. In order to minimize the interval required to re-stretch the sucker rods and increase the relation of the up stroke time to the down stroke time, the method is modified by starting the up stroke of the polish rod before the sucker rods have been re-stretched by their own inertia and weight, rapidly raising the polish rod until the sucker rods have been re-stretched, and thereafter slowly raising the polish rod until it completes its up stroke.

In the event that the sucker rod string is partially counterbalanced, such counterbalancing effect is sufficiently below the weight of the sucker rod string that the pumping cycles shown in chart B and C may be obtained.

Though I have shown and described certain embodiments of my invention and certain methods of operation, I do not wish to be limited to the precise disclosure herein made, but desire to include in the scope of my invention the constructions, combinations, and arrangements substantially as set forth in the accompanying claims.

I claim:

1. In a hydraulic pumping jack having a cylinder and a piston therein, said piston arranged to be raised by hydraulic pressure and to be lowered by the load on said jack; piston speed control means comprising: a plunger of reduced diameter projected downwardly from said piston; a socket in the lower head of said cylinder arranged slidably to receive said plunger; a channel arranged to permit the escape of hydraulic fluid from the lower end of said socket; a second channel arranged to permit the escape of hydraulic fluid from the annular space between said plunger and the wall of said cylinder; a regulating valve interposed in said second channel, and means for introducing hydraulic fluid under pressure into the lower end of said socket to move said piston upwardly at a relatively rapid rate until said plunger emerges from said socket and thereafter at a lower rate.

2. In combination with a hydraulic pumping jack and a pressure creating pump for actuating said jack, load counterbalancing means comprising: a substantially closed storage tank arranged to supply jack actuating fluid to the suction side of said pump during the power stroke of said jack and to receive said fluid during the return stroke, and means for maintaining automatically a substantially constant superatmospheric pneumatic pressure on the liquid supply within said tank.

3. In combination with a hydraulic pumping jack and a pressure creating pump for actuating said jack; load counterbalancing means comprising: a substantially closed storage tank arranged to supply actuating fluid to the suction side of said pump during the power stroke of said jack and to receive said fluid during the return stroke, and means actuated by fluctuations in fluid pressure in said jack for maintaining a substantially constant superatmospheric pneumatic pressure on the liquid supply within said tank.

4. In a hydraulic pumping jack for a well having a casing therein: a unitary housing structure supported by said well casing, said housing structure including a jack cylinder receiving socket disposed coaxially with said well casing; a valve chamber formed within said housing; a channel for the passage of pressure fluid between said chamber and said socket; an axial bore through said housing for the passage of a reciprocating rod from said socket into said casing; a packing gland arranged to surround said rod, and means formed on the lower end of said housing for attaching said housing to the upper end of said casing coaxially therewith.

5. In a hydraulic pumping jack assembly including a cylinder, a piston reciprocating therein, said piston arranged to be raised by hydraulic pressure and lowered by the load on said jack, a reservoir for hydraulic fluid, and pressure creating means adapted continuously to deliver a stream of hydraulic fluid of constant volume; valve means comprising: a valve chamber rigidly affixed to said cylinder; a cylinder port connecting said chamber with the lower end of said cylinder; an exhaust port connecting said chamber with said reservoir; a pressure port connecting said chamber with said source of pressure fluid; a valve member within said chamber, said member having two independent passages within its body arranged to connect said cylinder port with said pressure port while closing said exhaust port and alternatively to connect both said cylinder port and said pressure port with said exhaust port, and means responsive to the movement of said piston to reciprocate said valve member alternately to make said connections.
